WATER COOLED FURNACE WALL

Filed Nov. 28, 1928

FIG. 1

FIG. 2

BY

Oscar Nygaard
J. H. McReady,
his ATTORNEY

INVENTOR

UNITED STATES PATENT OFFICE

OSCAR NYGAARD, OF SAUGUS, MASSACHUSETTS

WATER-COOLED FURNACE WALL

Application filed November 28, 1928. Serial No. 322,468.

This invention relates to water cooled furnace walls.

In co-pending applications I have disclosed various constructions of furnace walls having tubes associated with them to conduct a fluid medium which serves to carry heat away from the wall and thereby to reduce the temperature of the wall. Such walls are commonly referred to as "water cooled walls" even though some other fluid medium is circulated through the tubes.

The present invention aims particularly to improve the means for holding the tubes and refractory blocks composing such a wall in cooperative relationship to each other. In certain of these walls it is desirable to have the tubes carry the bricks which make up the wall or certain parts of it, and the invention provides an exceptionally satisfactory construction for this purpose.

The nature of the invention will be readily understood from the following description when read in connection with the accompanying drawings, and the novel features will be particularly pointed out in the appended claims.

In the drawings,

Figure 1 is a front elevation of a part of the furnace wall constructed in accordance with this invention;

Fig. 2 is a side elevation of the section of wall shown in Fig. 1;

Fig. 3 is a horizontal sectional view on the line 3—3, Fig. 1; and

Fig. 4 is a perspective view of one of the blocks used in the wall shown in the other figures.

The drawings show the invention applied to a wall of the type shown and described in my pending application Serial No. 286,128 although it should be understood that this disclosure is made rather by way of illustration than limitation and that the invention can be used in a great variety of other wall constructions. The wall illustrated comprises a series of tubes 2 designed to conduct water, steam, or other fluid. When this wall is used in a boiler furnace the tubes sometimes are connected into the circulating sys-

tem of the boiler, and in other installations feed water is circulated through the tubes.

Closely associated with these tubes are bricks 3, each of these bricks including a portion which lies in front of the tubes, and another part that projects rearwardly between the tubes and partly encircles one of the tubes. Considering any pair of tubes, as for example, the two right-hand tubes shown in Fig. 1, it will be observed that each of the bricks 3 has a tapered projection *a* extending laterally therefrom and fitting into a recess formed in or between the next two laterally adjacent bricks. Also, that the upper and lower surfaces of each projection *a* are inclined. The bricks in contact with each tube rest end to end, one on the other, in a vertical series, and the two series of bricks in contact with adjacent tubes have their inclined surfaces bearing on each other, these surfaces tending to cause the bricks to gravitate one on the other into contact with their respective tubes. For a more complete description of the construction of this wall reference should be made to the pending application above identified.

In many installations it is desirable to have the tubes support the bricks, and the present invention provides a clamp construction which is particularly useful for this purpose. As shown, this clamp comprises an angle bar or channel bar, the latter preferably being used, to which a series of the tubes 2 is secured. This channel bar is shown in the drawings at 4. It is located transversely to and immediately behind the tubes 2. A U-bolt 5 partly encircles each tube, and its legs project through holes in the channel bar 4. Interposed between each tube 2 and the channel bar is a block 6 which rests between the flanges of the channel bar and is provided at its forward side with a boss *b*, Fig. 4, having a curved surface to fit against one of the tubes 2. The block preferably is made of such dimensions that this curved face projects in front of the edges of the flanges of the channel bar, as clearly shown in Figs. 2 and 3, and the block also is provided near its opposite ends with holes *c*, Fig. 4, to receive the legs of one of the U-bolts 5.

These blocks approximately fill the space in the channel bar between the respective tubes 2 and the upright web of the bar, as clearly shown in the drawings. When the nuts of the bolts are tightened the tubes are secured rigidly to the bar and each block 6 is clamped firmly between the web of the bar and its respective tube. The blocks or bricks which compose the front section or facing of the wall are herein called "bricks" for convenience, regardless of the material of which they are made, and the elements 6 are referred to as "blocks".

The bar 4 effectually resists longitudinal bending because of its flanged construction but the tightening of the nuts on the U-bolts tends to buckle this bar. Such a tendency, however, is effectually resisted by the blocks 6 which bear against the tubes and also against the web of the channel bar at points immediately beside the legs of the bolts. In addition, the blocks provide ample contact with the tubes to take the pressure applied in clamping the bar to them.

It will be clear from an inspection of the drawings that those bricks 3 which are in contact with the U-bolts 5 and are located partly or wholly above the U-bolts, are grooved or recessed to receive these bolts. In other words, each of these bricks has a shoulder to rest on one of the U-bolts. Each of these bricks, therefore, is supported by its contact with one of the bolts 5, and these bolts are clamped rigidly to the tubes by the construction above described. Those bricks which rest on the bricks mounted directly on the U-bolts are supported by the latter bricks. A sufficient number of these clamps is used so that no one of them is obliged to carry an excessive weight. For example, the lowermost right-hand U-bolt shown in Fig. 1 directly supports the half brick 3' and through it supports the four bricks 3 which are located in line with and above it. The brick 3'' rests on and is supported by the U-bolt 5, and it may carry also the weight of several bricks above the brick 3''. Due to the peculiar construction of the bricks and to the way in which their inclined surfaces act on each other, each U-bolt cannot be said to support solely the weight of a series of bricks in contact with the particular tube to which it is clamped, although this is approximately true, but the U-bolts of two adjacent tubes cooperate to support the weight of two series of bricks located between and in contact with said tubes and with each other.

In addition to supporting the weight of the bricks, the clamping constructions above described are particularly valuable also in securing the tubes rigidly together and holding them in proper alinement. The channel bars may be made of any suitable length, and if desired may be arranged in sets, the bars of each set being shorter than the width of

the series of tubes, and the bars of the upper set being staggered with reference to those in the lower set.

It is desirable to recess the rearward side of each of the blocks 6 as shown, for example, at d in Figs. 3 and 4, this recess preferably being provided in the region between the holes c for the U-bolts so that the contact area between the blocks and the channel bars will be reduced and the rate of conduction of heat from the tubes to the channel bars will be correspondingly lessened.

This construction has the advantage of being economical to manufacture, convenient to install, and readily adaptable to the variations encountered in installing walls of this type. The channel bars and U-bolts are standard products, and while the blocks 6 must be made specially, their manufacture requires merely a simple casting operation. The construction provides a very rigid and dependable support for the refractory bricks which protect the tubes and give strength and rigidity to the entire wall structure because of the fact that it clamps the tubes rigidly together and holds them in properly spaced relationship to each other.

A further advantage of this construction is that the channel bar forms a convenient anchorage for the bolts which hold the rear panel (not shown) of the wall in position. That is, a considerable thickness of heat insulating material usually is placed immediately behind the tubes and this material is held in position by a shell or panel which must be anchored in some way to the other parts of the wall structure. The channel bars form a convenient support into which to thread the bolts that hold the shell in position.

While I have herein shown and described a typical embodiment of my invention, it will be understood that the invention may be embodied in other forms without departing from the spirit or scope thereof.

Having thus described my invention, what I desire to claim as new is:

1. In a water cooled furnace wall, the combination of a series of tubes located side by side; bricks positioned in protective relationship to said tubes; and means for supporting said bricks in cooperative relationship to said tubes; said means comprising a flanged bar extending transversely to said tubes and located immediately beside them, blocks fitting between the respective tubes and said bar, and devices bearing against the sides of the tubes remote from said bar and provided with screw threaded parts cooperating with the bar to secure the tubes to the bar and to clamp said blocks between the respective tubes and the bar.

2. In a water cooled furnace wall, the combination of a series of tubes located side by side; bricks positioned in protective relation-

ship to said tubes; and means for supporting said bricks in cooperative relationship to said tubes; said means comprising a flanged bar extending transversely to said tubes and located immediately beside them, blocks fitting between the respective tubes and said bar and having curved faces to bear against the respective tubes, and devices bearing against the sides of the tubes remote from said bar and provided with screw threaded parts cooperating with the bar to secure the tubes rigidly to the bar and to clamp the blocks between the respective tubes and the bar.

3. In a water cooled furnace wall, the combination of a series of tubes located side by side; bricks positioned in protective relationship to said tubes; and means for supporting said bricks in cooperative relationship to said tubes; said means comprising a flanged bar extending transversely to said tubes and located immediately beside them, blocks fitting between the respective tubes and said bar and having curved faces to bear against the respective tubes, and devices bearing against the sides of the tubes remote from said bar and provided with screw threaded parts projecting through said bar and blocks, said devices serving to secure the tubes to the bar and to clamp said blocks between the respective tubes and the bar.

4. In a water cooled furnace wall, the combination of a series of tubes located side by side; bricks positioned in protective relationship to said tubes; and means for supporting said bricks in cooperative relationship to said tubes; said means comprising a flanged bar extending transversely to said tubes and located immediately beside them, blocks fitting between the respective tubes and said bar and having curved faces to bear against the respective tubes, and U-bolts partly encircling the respective tubes and projecting through the bar, said U-bolts serving to secure the tubes to the bar and to clamp said blocks between the respective tubes and the bar.

5. In a water cooled furnace wall, the combination of a series of tubes located side by side; bricks positioned in protective relationship to said tubes; and means for supporting said bricks in cooperative relationship to said tubes; said means comprising a flanged bar extending transversely to said tubes and located immediately beside them, blocks fitting between the respective tubes and said bar, and screw threaded devices engaging the faces of said tubes remote from the bar but projecting through the bar and serving to secure said tubes to the bar and to clamp said blocks between the respective tubes and the bar, said blocks being shaped to provide a relatively small area of contact with the bar.

6. In a water cooled furnace wall, the combination of a series of tubes located side by side, a flanged bar extending transversely to said tubes and located immediately beside

them, blocks fitting between the bar and said tubes, U-bolts engaging said tubes and projecting through said bar and serving to secure the tubes to the bar and to clamp the blocks between the respective tubes and the bar, and bricks located in protective relation to said tubes and supported on said bolts.

7. In a water cooled furnace wall, the combination of a series of tubes located side by side, a flanged bar extending transversely to said tubes and located immediately beside them, blocks resting in the flange part of the bar and having curved faces to bear against the respective tubes, and U-bolts partly encircling the respective tubes and extending through the bar and said blocks, said bolts serving to secure the tubes to said bar and to clamp said blocks between the respective tubes and the bar.

8. In a water cooled furnace wall, the combination of a series of tubes located side by side; bricks positioned in protective relationship to said tubes; and means for supporting said bricks in cooperative relationship to said tubes; said means comprising a bar extending transversely to said tubes and located immediately beside them, blocks fitting between the respective tubes and said bar and having curved faces to bear against the respective tubes, and bolts bearing against the sides of the tubes remote from said bar and provided with screw threaded parts cooperating with the bar to secure the tubes rigidly to the bar and to clamp the blocks between the respective tubes and the bar.
